BALL POINT WRITING INSTRUMENT

Filed Sept. 20, 1945

UNITED STATES PATENT OFFICE

2,588,629

BALL POINT WRITING INSTRUMENT

Philip C. Hull, Janesville, Wis., assignor to The Parker Pen Company, Janesville, Wis., a corporation of Wisconsin

Application September 20, 1945, Serial No. 617,518

1 Claim. (Cl. 120—42.03)

1
This invention relates to ball-point writing instruments and has for its primary object to provide a simple, low-cost device of that character wherein the writing point is retractable into the holder and subsequently propellable therefrom into operating position by depressing a pushbutton at the back end of the holder.

Another object is to provide a writing instrument of the above-indicated character wherein the ball point and ink reservoir are incorporated in one self-contained unit which is easily removable for replacement or refilling when the ink supply needs replenishing.

The present invention is characterized by the provision of a two-position spring detent mechanism which, on the one hand, holds the writing point in its projected position securely enough to resist normal writing pressure but yieldable sufficiently to permit the writing point to be retracted into the holder by the application of pressure which is only slightly greater than the maximum writing pressure, and which, on the other hand, securely latches the writing point in its retracted position so that it cannot drop out of the retracted position except when propelled by actuation of the aforementioned pushbutton.

For purposes of illustration, a practical embodiment of the invention is shown in the drawings, wherein:

Fig. 1 is a longitudinal sectional view of a pushbutton operated ball-point writing instrument embodying this invention, the writing point being shown in retracted position;

Fig. 2 is identical with Fig. 1 except that the writing point, together with the propelling and retracting mechanism, are shown in the projected or propelled position; and

Fig. 3 is a cross-sectional view taken along line 3—3 of Fig. 1.

The writing instrument illustrated comprises an elongate tubular holder 1 which includes a barrel 2 which may be of plastic material, and a tapered tip member 3 made, preferably, of metal and threaded into the forward end of the barrel.

Housed within the holder is a ball-and-cartridge unit 4 comprising an elongate cartridge 5 which serves as an ink reservoir and to which is attached a feed tube 6 in the front end of which is seated a ball point 7, which serves as the writing point of the instrument. The reservoir is filled with a viscous, paste-like ink which is conducted through the bore 6a of tube 6 to the back of ball 7. A coil spring 8 continuously urges the ball-and-cartridge unit toward its retracted position shown in Fig. 1.

2
Pressed into the rear end of barrel 2 is a metal bushing 9 which serves as a bearing for the rear end of the ball-and-cartridge unit 4 while at the same time serving to hold in place a pocket clip 10 which is inserted through a slot 11 in the barrel wall. Clip 10 has a tail piece 10a which is clamped between the outside of bushing 9 and the inner wall of barrel 2. Threaded into the extreme back end of the barrel is a bushing 12 through which a plunger 13 extends. The forward end of plunger 13 has an integral flange 14 which bears against the back end of ball-and-cartridge unit 4. This plunger also has a small head 15 at its back end on which is pressed a cup-like member 16, the rear end portion of which constitutes a push-button. The forward part of member 16 is slotted longitudinally to form a number of spring fingers 17, each terminating in a bead or bulge 18.

20 The spring fingers 17 are of such length that when the pushbutton 16 is fully depressed and the ball-and-cartridge unit 4 is moved to its fully propelled position, the beads 18 extend beyond and snap behind the inner end 20 of bushing 12 normally holding the ball-and-cartridge unit in its forward or propelled position. The spring 8 is not of sufficient strength to overcome the holding effect of the spring fingers 17 and beads 18 but it is of sufficient strength to hold the ball-and-cartridge unit 4 firmly against the plunger 13 and the beads 18 in firm engagement with the inner end 20 of the bushing 12 thereby positively positioning the writing point 7 for writing.

The rearward or retracted position of the ball-and-cartridge unit 4 is determined by an annular V-shaped groove 19 formed in the bore of the bushing 12. This groove is so located that when the beads 18 are fully seated therein the writing point 7 is fully retracted into the barrel as shown in Fig. 1. To retract the writing point to the position shown in Fig. 1, the user simply places the writing point against a suitable surface, as for example a desk blotter, and presses it back to a position flush with the outer end of the barrel tip 3. The V-shaped groove 19 is so located longitudinally that when the writing point is moved as just described, the beads 18 engage the outer part of the lower tapered side wall of groove 19 which side wall, acting as a cam, causes the beads to snap or ride fully into the groove 19 under the influence of spring 8 which is then yieldably urging the ball-and-cartridge unit 4, plunger 13 and pushbutton 16 rearwardly. This results in the writing point being further and quickly retracted from the flush

position above mentioned to the fully retracted position of Fig. 1. When the beads 18 are disengaged from the inner end of the bushing 12 by the aforementioned push action, the spring 8 is not depended upon to move the retractable structure to its fully retracted position because of the frictional engagement of the beads with the inner wall of the bushing, but the spring 8 does become effective as the friction is sufficiently reduced as the beads enter the groove 19. In the fully retracted position the spring 8 yieldably urges the ball-and-cartridge unit 4 against the plunger 13 but it is not of sufficient strength to disengage the beads 18 rearwardly from the groove 19.

It will be obvious from the foregoing that, with the ball-and-cartridge unit fully retracted as shown in Fig. 1, depression of the pushbutton 16 will result in the beads 18 being forced out of the groove 19 and the ball-and-cartridge unit being propelled forwardly against the action of spring 8 to its fully propelled position of Fig. 2. As soon as the pushbutton 16 has been fully depressed, the beads 18 snap behind and into latching engagement with the inward end 20 of bushing 12 thus yieldably latching the ball-and-cartridge unit 4 in its propelled or projected position of Fig. 2. Retraction of the unit is accomplished as explained above. The ball-point is usually coated with ink which might soil the user's clothing and this is avoided by fully retracting the point into the holder.

The spaces between the spring fingers 17 provide vent passages leading from the interior of the barrel 2 except when the plunger 13 is substantially entirely depressed. Ball-and-cartridge unit 4, plunger 13 and pushbutton 16 are readily withdrawable from the holder by unscrewing and removing bushing 12.

I claim:

In a writing instrument, a hollow elongate holder having a bore opening at its front end, a writing unit having a writing point at its front end, means slidably mounting said unit in said holder whereby it is capable of being propelled forwardly to project said writing point out of the front end of said bore into writing position and of being retracted to move said writing point

into said holder, said writing unit being of substantially the same diameter as said bore for the greater part of its length, a reduced diameter pushbutton engageable with said unit adapted to project out of the rear end of the holder, said pushbutton being operative, upon being depressed, to propel said writing unit forwardly, a plurality of circumferentially spaced, laterally movable, outwardly urged spring fingers secured to said pushbutton, said holder having longitudinally spaced circumferential formations for receiving said spring fingers, said circumferential formations and spring fingers having interengaging camming surfaces, said spring fingers when in one of said circumferential formations being operative to hold said writing unit in its projected position against ordinary writing pressure but yieldable to retractive pressure applied longitudinally to the writing point when said retractive pressure is substantially greater than ordinary writing pressure.
